UNITED STATES PATENT OFFICE

CALVIN E. MILLER, OF BETHLEHEM, PENNSYLVANIA

THERAPEUTIC APPARATUS

Application filed March 18, 1930. Serial No. 436,802.

This invention relates to therapeutic apparatus, such as used by osteopathic physicians or others administering mechanical treatments, and aims to provide a novel, efficient and unitary form of apparatus for performing automatically many of those treating operations peculiar to the art of osteopathic therapeutics which have heretofore been performed by hand.

10 One of the primary objects of this invention is to provide an apparatus similar in principle to the apparatus disclosed in my pending application, Serial No. 342,374, filed February 25, 1929, but of more simple construction.

Another object of this invention is to provide an apparatus of this character which will be highly efficient, have few parts, be economical to manufacture and practically trouble and service free.

Generally speaking, this apparatus comprises a cabinet-like support for a recumbent body which houses a power-driven mechanism for imparting a pulling action to straps to which are attached resilient pads adapted to engage the chest and abdomen or other parts of the body as the case may be. The functions of the body engaging members are to impart pulsating pressures to the body in positive alternating relation to each other. An auxiliary mechanism is provided to impart rapid vibrations by means of another strap which may be applied to various portions of the body as desired.

25 This apparatus, by its pumping action on the body, is particularly adapted to increase the normal flow or movement of the lymph from the tissues and organs of the body into the blood stream and return the venous blood back to the heart quickly and supply fresh nutritive lymph. However, it is not limited to this function alone, as it is well adapted to treat the spine or other parts of the body. When used to increase the flow of the lymph 30 the patient lies on his back but when used for

spinal or other treatment the body is positioned accordingly on the support.

This apparatus is adapted to be embodied into a portable cabinet having folding ends or it may be attached to any of the standard office treating tables, by means of special attachments adapted to the design of the respective tables, but for uniformity I have chosen to illustrate and describe the portable species.

55 The novel features will be more fully understood from the following description and claims taken with the drawings in which:

Fig. 1 is a perspective view of the apparatus showing the support for the body, the folding end members and the relation of the body engaging members.

Fig. 2 is a cross sectional view taken through the support on line 2-2 of Fig. 3 showing its box-like construction and the actuating mechanism therein.

Fig. 3 shows the plan of the operating mechanism when viewed from the under side of the machine.

Fig. 4 is a plan view of the mechanism as seen in Fig. 3 but viewed looking down and in the opposite direction to that of Fig. 3 with the bed plate removed.

Fig. 5 is a plan view of the abdominal pad.

Fig. 6 is a detailed view of a rocker arm and hook assembly.

Fig. 7 is a plan view of the chest pad.

Fig. 8 is a sectional view of the speed reducing gear shown in Fig. 3.

Fig. 9 shows a pad and strap assembly in combination with a hand-operated adjusting and tensioning device.

Fig. 10 is an enlarged view showing a preferred form of make-up of the strap members.

Fig. 11 is a sectional view similar to Fig. 2 but shows the manner in which the vibrating strap is operated and applied.

Fig. 12 is a section taken longitudinally through the apparatus and shows the de-

tails of the cabinet and the folding end members.

Fig. 13 is a detail of the locking device for retaining the leg support in its closed position and for retaining the supporting member in its opened or operative position.

Referring to Fig. 1, numeral 20 indicates generally an upholstered cabinet which forms a support for a recumbent body, and is adapted to house the mechanism which operates the straps and pads. The cabinet comprises a rectangular box shaped middle portion 21 which contains the operating mechanism. A hinged head rest 22 is attached to the upper end of the support and is adapted to fold downwardly against the ends of the side pieces 23 to close the open end of the cabinet when not in use. The head rest is supported in its raised position by means of a collapsible toggle bracket 24 attached to the under side of the head rest and the bottom board 25 of the cabinet. The toggle comprises two hinged arms pivotally attached to brackets 26 and 27. The intermediate ends of the arms 28 are provided with hinged jaws adapted to abut each other when the arms are carried past the dead center of the bracket, which constitutes a point on a line intersecting the pivoted joints at the ends of the arms. When the jaws of the two arms are brought together, no further outward movement of the arms can take place, thus forming a rigid and self-locking support for the head rest when it is in raised position. A spring 28 is attached to each of the arms to hold the toggle in its locked position, and which also tends to hold the head rest against the end of the cabinet when in its lowered position. To lower the head rest a slight pressure is applied to the toggle bracket in a forwardly direction to break the joint. The action of the spring tends to collapse the joint and retain the head rest in the position as shown by the dotted lines in Fig. 12.

The leg support 29 is hinged to the lower end of the middle portion 21 and is made of less width than the distance between the inside faces of the side pieces 23 so that it can be folded downwardly as shown by the dotted line in Fig. 12. The length of the leg rest is longer than the head rest so as to provide a comfortable support for the lower portion of the body. The leg rest is supported in its raised position by means of a hinged leg 30 which is attached to the under side of the rest. The leg 30 has a spring pressed plunger 31 adapted to register with a hole in a bracket 32 which is attached to the leg rest for the purpose of locking the leg 30 in its operative position. Similar spring plungers 33 are inserted in the side pieces 23 to lock the leg support in its folded position. The plungers in this case register with pieces 34 which are attached to the bottom of the rest at opposite edges.

The top board 35 is upholstered in a suitable manner, likewise the end hinged members. The apparatus in this form is easily carried and serves a double purpose for office and out-patient work but it is to be understood that the operating mechanism and rollers may be attached to an office table as well.

The apparatus comprises two pressure members 36 and 37 which are adapted to engage the chest and abdomen respectively or other parts of the body as the treatment requires.

As shown in Fig. 7, the chest pad 36 consists of a piece of resilient material commonly called sponge rubber of about one and one quarter of an inch in thickness. Its length is sufficient to span the upper part of the chest from points just outside of the arm pits. This pad is made wider at its middle portion than at its ends so that its action is more widely distributed and effective than if it were uniform in shape throughout its length. Near each end of the pad is secured a keeper 38 under which the strap passes. This method of attaching the pad to the strap allows the pad to be slidably adjusted relative to the strap. The abdominal pad 37 is made of the same material as the chest pad but is comparatively smaller and is shaped so that its upper end will conform with the abdominal surface as outlined by the lower ribs. The shape of this pad is important for the proper distribution of pressure on this part of the body.

In Fig. 1 it will be noted that the straps shown thereon are plain single straps but I have found from experience that a strap made in the manner as shown in Figs. 9 and 10 is preferable. However, either style may be used. In the preferred form, the center portion 39 is in the form of a long loop which is provided at one end with a buckle 40 of the toggle type which requires no holes in the strap. To each of the looped ends are attached short single straps 41 having snap hooks 43 attached thereto.

Straps made up in this manner have a double advantage in that the slack of the strap may be taken up by pulling upwardly on the top course of the strap without disturbing the position of the pad when once properly located on the body. This is possible because the loops at the ends of the central strap 39 permit the looped ends to be brought closer to each other by sliding through the connecting links 44 without moving the pad; secondly, if it is desired to distribute the pull of the strap over a greater portion of the pad, the top course of the strap may be shifted so as to contact with the pad higher up, thus covering the pad to a greater extent than when the upper and lower portion of the strap are parallel or in line with each other.

In case it is desired to make repeated

changes of position of a pad without stopping the motor, the lever 45 is connected to the snap hook 43 and link 46 of the roller strap 47 as illustrated in Fig. 9. The lever is held in one hand of the operator and when pressed downwardly produces tension on the strap without disturbing the buckle adjustment thus regulating the pressure on the pad at will. When the pressure on the lever is released the strap and pad may be moved to another position while the machine is operating without readjusting the buckle.

At each side and underneath the top of the support or table are secured brackets 48 between which, rollers 49 are mounted. The brackets are designed so as to bring the rollers outside and free of the edge of the cabinet and yet not protrude to such an extent that they will interfere with the operator when the apparatus is applied to an office table. The bracket is preferably made in one piece with arms 50 at its ends and an intermediate arm 51. The rollers are rotatably mounted on a fixed shaft 52 which is carried by the bracket arms. This permits the rollers to rotate in opposite directions. Wood is preferred material for the rollers.

The operating mechanism is comparatively simple in design and comprises a motor 53, a speed reducing gear 54, a flexible coupling 55 connecting the shafts of the motor and the speed gear. The vertical or driven shaft 56 of the speed gear extends through the gear casing 57, and the driving crank 58 is keyed to the shaft as shown in Fig. 4. The motor and speed gear are mounted on a bed plate 59 which is adapted to be secured to the underside of the top board 35 of the cabinet, or it may be attached to members of an office table by means of suitable connections. The bed plate is of sufficient thickness to prevent springing and disalignment of the moving parts. The speed gear is spaced from the bed plates by means of hollow pieces 60 through which bolts 61 pass to secure the speed gear to the bed plate. On opposite sides of the speed gear are positioned rocker arms 62 and 63 which are mounted on wrist pins 64 secured to the bed plate. A washer 65 and pin 66 holds the arm in place on the wrist pin. A driving link 67 connects the crank arm 58 to the rocker arm 62 and rocker 63 is connected to rocker 62 by means of a cross connecting link 68 after the manner as shown in Figs. 3 and 4. To the rocker arms are attached pivotally mounted members 69, 70, 71 and 72 having hooked ends which provide the connections between the roller straps 47 and the driving mechanism. Means for lubrication are provided for all the moving parts.

On the extension of the worm shaft 73 is attached a rotatable member 74 having an arm 75 which is eccentric with the axis of the worm shaft for the purpose of connecting the

vibration strap 76 as shown in Fig. 11. It will be obvious that the worm shaft 73 will rotate at the same rate of speed as the motor, which in this case is about 1700 R. P. M., while the speed of the vertical shaft 56 driven by the worm wheel 77 will be considerably less; therefore, the crank arm 58 will travel at a lower speed than the vibrating member 74. The ratio of speed reduction between the motor and the rocker arms is a very important factor, as I have determined from actual practice that the pull on the body straps should be approximately at the rate of about 120 pulsations per minute to produce the most beneficial results.

For the purpose of describing the operation of my invention, it will be assumed that treatment of the chest and abdomen is desired. With the patient in a recumbent position on the table, the pads 36 and 37 are placed in their proper positions, and the straps are attached to the actuating mechanism. After this has been done, the slack in each strap is taken up to the desired tension and held in this condition by means of the buckle. On starting the motor, a rotary motion is imparted to the driving crank 58 through the speed gear, and the driving link 67 connecting the crank to the rocker arm 62 converts the rotary motion of the crank 58 into an oscillating motion of the rocker arm. The rocker arm 63 is cross connected to rocker 62 in such a manner so that the hooks 69 and 71 will be moved alternately to and from each other simultaneously which produces a corresponding pulling and releasing action of the straps attached to the hooks. A similar action will be imparted to the straps attached to hooks 70 and 72. It will be obvious that when hooks 69 and 71 are being drawn toward each other that hooks 70 and 72 will move in the opposite direction. Thus the motion imparted to the two different sets of straps will be of an alternating order which will produce alternating pressures on the body by means of the pads.

It will be noted that the rollers 49 have been made sufficiently long so as to allow the pads 36 and 37 to be placed at different distances apart, and for that reason the hooks have been pivotally attached to the rocker arms to allow of their alignment with the straps. The length of the rollers also provides for the longitudinal back and forth creeping action of the straps over the rollers due to the angular relation of the straps to the axis of the rollers which in some cases may be considerable, depending upon the position of the pads on the body.

Referring to Fig. 3, it will be noted that the angular lines of pull on the straps will intersect each other at a point 78 substantially on the center line of the machine and that the lines of pull diverge outwardly from

this point toward the rollers and upwardly over the top of the machine. Obviously, when the pads 36 and 37 are positioned on the body in spaced relation to each other a downward and forward motion is imparted to pad 36 and a downward and backward motion is imparted to pad 37. The term forward being considered as in the direction of the feet of the patient lying on the support, and backward being considered as in the direction of the head of the patient. This motion is particularly useful in the performance of certain treatments as applied to the chest and abdomen.

13 When using the vibrating apparatus the patient is placed in the position desired by the operator. The end 79 of the strap 76 is buttoned over the eccentric 75 and the other end is taken over the roller 49 at the edge of the 20 table and brought into contact with the body of the patient while the operator holds in his hand the free end of the strap and applies tension thereto. The action of the rapidly revolving eccentric thus imparts to the body a 25 vibrating motion, the vibration being equivalent to the speed of the motor which is about 1700 R. P. M. The vibrator may be used singly or in combination with the other straps if so desired.

30 It will be seen by the foregoing that I have provided a therapeutic apparatus which will automatically perform treatments in a manner which by actual practice by hand have proven most effective. Furthermore, 35 so far as I am aware, no apparatus of this nature has heretofore been devised which is adapted to be easily carried or transported for use outside of the office. Obviously, this novel feature adds greatly to its usefulness 40 as it can be easily brought to the patient who is too ill to make an office call. This feature alone greatly enhances its value.

While I have shown my invention in but one form it will be obvious to those skilled 45 in the art that it is not so limited, but is susceptible of various changes and modifications without departing from the spirit thereof, and I desire, therefore, that only such limitations shall be placed thereupon as are imposed by the prior art or as are specifically set forth in the appended claims.

I claim:

1. In a therapeutic apparatus comprising a support for a body; a plurality of straps 50 operatively disposed above said support and adapted to engage spaced portions of the body, means located under said support to alternately reciprocate said straps, said means comprising a motor, a speed reducing gear driven by the motor, rocker arms positioned on opposite sides of said gear, a crank 55 driven by said gear, means connecting said crank and one of said rocker arms and means connecting said rocker arms, whereby one of 60 said rocker arms is operated directly by said 65

crank and the other of said rocker arms is operated through the intermediary of the directly operated rocker arm.

2. In a therapeutic apparatus comprising a support for a body; a plurality of straps 70 having pads connected thereto operatively disposed above said support and adapted to engage spaced portions of the body, means located under said support to alternately reciprocate said straps and said pads, said means comprising a motor, a speed reducing gear driven by the motor, rocker arms positioned on opposite sides of said gear, a crank 75 driven by said gear, a driving link connecting said crank and one of said rocker arms, a cross link connecting said rockers, and hooks pivotally connected to said rockers for attaching said straps thereto.

3. In a therapeutic apparatus comprising a support for a body; a plurality of straps 80 having pads connected thereto operatively disposed above said support and adapted to engage spaced portions of the body, rollers positioned at the sides of said support over which said straps pass to the underside of 85 the support, means located under said support to alternately reciprocate said straps and said pads, said means comprising a motor, a speed reducing gear driven by the motor, rocker arms positioned on the opposite 90 sides of said gear, a crank driven by said gear, a driving link connecting said crank and the end of one of said rocker arms, a cross link connecting the diagonally opposite 95 ends of said rocker arms, and pivoted 100 connections on said rockers for attaching said straps thereto.

4. In a therapeutic apparatus, a portable support for a body, comprising a shallow box-like middle portion having hinged end 105 members attached thereto to form extensions to the middle portion, straps operatively disposed above said support and adapted to engage spaced portions of the body, mechanism located inside of the middle portion of said support to reciprocate said straps to produce alternating pressures on the body, said mechanism comprising a motor, a speed reducing gear driven by the motor, rocker arms positioned on opposite sides of said gear, a crank 110 driven by said gear, means connecting said crank and one of said rocker arms and means connecting said rocker arms, whereby one of 115 said rocker arms is operated directly by said crank and the other of said rocker arms is 120 operated through the intermediary of the directly operated rocker arm.

5. In a therapeutic apparatus comprising a box-like support for a body; a plurality of straps having pads connected thereto operatively disposed above said support and adapted to engage spaced portions of the body, mechanism located inside of said support to reciprocate said straps and said pads to produce alternating pressures on the body, said 125 130

support having spaced side pieces of greater height at one end than at the other end, a top piece connecting the two side pieces at their top edges, a bottom piece connecting the side pieces at their lower edges, a hinged head rest attached to said top piece and adapted to swing downwardly against the ends of said side pieces, means to support said head rest in its raised position, a leg support hinged to the forward end of said top piece and adapted to swing downwardly and under said top piece, and means to support the leg rest in its raised position.

6. In a therapeutic apparatus comprising a portable support for a body; straps having pads connected thereto operatively disposed above said support and adapted to engage spaced portions of the body, mechanism located inside of said support to reciprocate said straps and said pads to produce alternating pressures on the body, said support having a shallow box-like middle portion with open ends and an inclined top, a swinging head rest attached to one end of said top, a swinging leg rest attached to the other end of said top, means to support said rests in their raised positions and means to retain said rests in their inoperative positions, said leg rest being of greater length but of less width than said head rest so as to swing downwardly and under the top of said support, the top of said middle portion and said swinging rests being covered with resilient material to form cushions.

35 7. In a therapeutic apparatus comprising a portable support for a body; straps having pads connected thereto operatively disposed above said support and adapted to engage spaced portions of the body, said support embodying a shallow box-like middle portion enclosing a mechanism adapted to reciprocate said straps and said pads to produce alternating pressures on the body, openings in the sides of said box, brackets positioned in said openings and carrying rollers over which said straps pass to the inside of the box and connect with said mechanism, said brackets being secured to the top member of the box and adapted to support fixed shafts on which said rollers revolve, said rollers being of greater length than the width of said straps to allow for longitudinal creep and adjustment of the straps.

55 8. In a therapeutic apparatus comprising a support for a body; a plurality of straps having pads slidably connected thereto operatively disposed above said support and adapted to engage spaced portions of the body, rollers positioned at the sides of said support over which said straps pass to the underside of the support, means located under said support to alternately reciprocate said straps and said pads and to impart vibrations to an additional strap, said means comprising a motor, a worm shaft driven by the motor, a worm

wheel and shaft driven by the worm, a crank mounted on the worm wheel shaft, rocker arms positioned on opposite sides of said worm and worm wheel, links connecting said rocker arms with said crank, and an eccentric member mounted on an extension of said worm shaft for directly attaching said additional strap thereto to rapidly vibrate the same.

In testimony whereof I hereunto affix my signature.

CALVIN E. MILLER.
